UNITED STATES PATENT OFFICE.

ORSON R. VAN SICKLE, OF TOLEDO, OHIO, ASSIGNOR OF ONE-HALF TO PAUL BUR-
SMITH, OF TOLEDO, OHIO.

COMBINATION SHADE, CURTAIN, AND DRAPERY FIXTURE.

Application filed April 23, 1924. Serial No. 709,326.

To all whom it may concern:

Be it known that I, ORSON R. VAN SICKLE, a citizen of the United States, and a resident of Toledo, in the county of Lucas and 5 State of Ohio, have invented a new and useful Combination Shade, Curtain, and Drapery Fixture, which invention is fully set forth in the following specification.

This invention relates to combined shade, 10 curtain and drapery fixtures for windows, and has for its object the provision of a simple, strong and inexpensive fixture of this class which is adapted to have curtain and drapery bars, or either, easily and 15 quickly attached thereto or detached therefrom.

The invention is fully described in the following specification, and while in its broader aspect it is capable of embodiment 20 in different forms, a preferred embodiment thereof is illustrated in the accompanying drawings, in which,—

Figure 1 is a top plan view of a pair of fixtures embodying the invention with a 25 shade roller and curtain and drapery bars carried thereby and partly broken away. Fig. 2 is an outer side elevation thereof. Fig. 3 is a perspective view of the two fixture members in operative relation, and Fig. 30 4 is an end view of one of the curtain or drapery bars.

Referring to the drawings, 1 and 2 designate the shade fixtures, each of which is stamped in L-shape from sheet metal to 35 form the base flange or foot 3 and the outwardly projecting bearing arm 4. The base flange of each fixture is perforated at 5 to receive nails or other suitable securing means for attaching it to a window casing, 40 and the arm 4 of one fixture is provided near its outer end with the bearing opening 6 while the arm of the other fixture is provided with the slot 7 to receive the respective circular and flat journaled stud members of the shade roller 8, as is customarily 45 the case.

A bracket member is formed on the upper edge of its arm 4 near its inner end with an integral finger 9 of L or hook shape, 50 which is bent outwardly to horizontal position with its inner edge parallel to and co-operating with the upper edge portion of the flange 3 to form an elongated slot-like opening 10, the outer end of which is closed 55 by the hooked or laterally projecting end

portion of the finger which rests at its free end on the top edge of the flange 3. The purpose of the fixture fingers 9 is to provide a member on each fixture with which the adjacent end of a curtain bar 11 or drapery bar 12, or both, may have hooked engagement 60 to retain it to the fixture. To enable a bar to be placed in hook engagement with fixture finger 9 the top edge of the bar is provided with a notch 13 for receiving the outwardly extending portion of the respective finger, and the edge portion of the bar, which is in advance of and forms the outer wall of the notch 13, forms a stud 14 which is adapted to be projected up into the respective fixture opening 10 and has its inner edge inclined or of hooked form to adapt it to have holding engagement with the inner wall of the finger. The bars 11 and 12 are 65 of flat form in vertical dimensions, thereby 70 adapting the bars to extend a distance below the fingers 9 when engaged therewith so that their ends may have end abutment 75 against the front sides of the fixture flanges 3 and co-operate with the fingers 9 80 to hold the bars in horizontal position, as is apparent. The bars 11 and 12 are preferably of the longitudinally adjustable type to adapt them to be adjusted to suit the spacing of the fixture members. In order to 85 maintain the leg portions of the two bars 11 and 12 in transversely spaced relation when 90 engaged to the fixtures 1 and 2, the base flange 3 of each fixture is formed substantially centrally of its side edges with a ridge 95 15 to project between the adjacent ends of the two bars.

It is evident that I have provided a simple and inexpensive shade roller fixture of stamped sheet metal form and with which 95 one or more curtain and drapery bars may be easily and quickly engaged.

Having thus described my invention, what I claim as new and desire to secure 100 by Letters Patent is:

1. A one-piece stamped shade roller fixture having a base flange, a bearing arm projecting outwardly from one edge of the flange, and an L-shaped finger formed on the upper edge of the bearing arm integral therewith and projecting laterally therefrom in forwardly spaced relation to the flange to form an elongated space between the finger and base flange to receive the hooked end of a drapery bar for engagement with 105 110

its finger, the outer end of said space being closed by the angled end of the finger.

2. A stamped shade roller fixture having a base flange and an outwardly projecting bearing arm, the arm being formed with an integral laterally projecting finger which co-operates with the base flange to form an

opening for receiving a portion of a curtain or drapery bar for engagement with the finger, and the base flange having a bar 10 spacing projection on its front side.

In testimony whereof I have hereunto signed my name to this specification.

ORSON R. VAN SICKLE.
